DISPLAY SIGN

Benton N. Reamer, Jersey City, N. J.

Application June 2, 1938, Serial No. 211,370

4 Claims. (Cl. 40—101)

The invention relates to display signs and has to do particularly with that type of sign in which a series of cartoons or pictures in continuity may be intermittently shown for advertising various products or enterprises. While the sign has been primarily designed for outdoor use it may readily be used indoors.

The principal object of the invention is to provide a sign which is extremely compact in construction and will permit of the display of a substantial amount of advertising matter.

A further object is to provide a sign which is strong and rugged in construction and one that will readily withstand the elements, particularly high winds.

A further object is to provide a sign of extremely simple construction which will require practically no attention except when it is desired to change the displays.

With the foregoing objects in view and others that will become apparent as this specification proceeds, the invention will be hereinafter described and one embodiment thereof illustrated in the accompanying drawings. Referring to said drawings:

Fig. 1 is a front elevation with parts broken away;

Fig. 2 is a side elevation;

Fig. 3 is a sectional view taken on line 3—3 of Fig. 1;

Fig. 4 is a sectional plan view taken on line 4—4 of Fig. 1; and

Fig. 5 is a detail sectional view showing the connection between one of the supporting rods and the chain.

In the drawings the structural work supporting the sign has been omitted as it may be widely varied and forms no part of the invention. The face of the bulletin board or sign is indicated at 10 in Figs. 2 and 3 and the face bears suitable advertising matter and is provided with an opening 11 through which the intermittently moved sheets or panels of subject matter may be viewed.

The sign comprises a plurality of sheets or panels 12 arranged as a continuous curtain and formed of canvas or some other suitable flexible material upon which a series of pictures or cartoons may be painted or posted. The upper edge, when viewed from the front of the sign of each sheet or panel is removably clipped as indicated at 13 to a supporting rod 14. The lower edge of each sheet or panel 12 is secured to a weighted rod 15 and this lower edge is removably clipped as indicated at 16 to the supporting rod 14. One or more extra spanner strips 17 may be utilized

to maintain the lateral edges of the sheets in parallel relation.

The weighted rods 15 are substantially coextensive with the width of the sheets 12. The supporting rods 14 extend beyond the lateral edges 5 of the sheets and their ends are carried by a sprocket chain 20. As shown in Fig. 5 the links carrying the supporting rods 14 may be thickened or provided with bosses and pins 21 may be used to prevent disengagement of the supporting rods from the sprocket chains.

The ends of the supporting rods 14 intermediate the sprocket chain 20 and the sheets 12 are provided with guide rollers 23 which engage continuous tracks 24, one on either side of the sign. 15 The tracks have front portions 25 and rear portions 26 which are connected at their upper ends by rounded portions 27 and at their lower by what might be termed storage portions 28. The storage portions of the tracks are angularly disposed from front to rear for reasons that will be hereinafter apparent. The curved upper portions 27 of the tracks substantially conform to the circumference of a large drum 30 over which the sheets pass.

The operation of the sign is dependent upon a positive drive and gravity. When the sheets or panels are being drawn from the storage portions 28 of the tracks, the positive drive is relied on. After the sheets have passed over the drum 30 into their display position gravity takes care of the operation. As the sheets pass downwardly after moving over the drum the rollers 23 will slide by gravity along the sloped regions of the storage portions 28 of the tracks and the rollers 35 will come to rest with the sheets draped or in folds as shown in Fig. 3. Obviously as shown in Fig. 2 the sprocket chains 20 will assume the same general formation.

The drive will now be described. The drum 30 is provided with sprockets 31 at both ends for engagement with the sprocket chains 20, and the pitch diameter of the sprockets 31 is substantially the same as the diameter of the drum and the radius of the rounded portions 27 of the tracks. 45 The drum 30 and its sprockets 31 are secured to a shaft 32. Freely mounted on the shaft 32 is another sprocket 33 which is engaged by a sprocket chain 34 which is driven through suitable gearing 35 from a motor 36. The sprocket chain 34 has secured to it a dog 37 which contacts with either one of a pair of stops 38 mounted on the drum 30. The dog 37 in its travel engages one of the stops 38 and the drum is rotated one-half a revolution which is sufficient 55

to advance one sheet past the display opening. The dog then slides off the stop and this sheet remains in view until the dog contacts the next stop. The intermittent movement of the sign 5 is thus provided for.

Means are provided for supporting the sheets to prevent buckling or bellowing due to high wind pressure. This means comprises a rigid plate 40 suitably supported by the sign structure. As each one of the sheets comes up for display, it is in contact and backed up by the plate 40 as shown in Figs. 3 and 4, thus forming an effective means for preventing bellowing or buckling of the sheets and greatly adding to the 15 life of the sign.

Changes in details of construction and arrangements of parts such as would occur to one skilled in the art are to be considered as coming 20 within the spirit of the invention as set forth in the appended claims.

I claim:

1. A display sign having in combination, a plurality of sheets arranged as a continuous curtain, supporting rods for said sheets, guide rollers 25 on the ends of said supporting rods, a continuous track cooperating with said rollers for guiding said sheets, a storage portion in the lower region of said track, a pair of sprocket chains substantially the same length as said curtain for carrying said supporting rods, and means for intermittently moving said sprocket chains so as 30 to raise said sheets from said storage portion, the sheets moving back into said storage portion under the force of gravity.

35 2. A display sign having in combination, a plurality of sheets arranged as a continuous cur-

tain, supporting rods for said sheets, guide rollers on the ends of said supporting rods, a continuous track cooperating with said rollers for guiding said sheets, a storage portion in the lower region of said track, a drum over which said 5 curtain passes, the upper portion of said track substantially conforming to the circumference of said drum, sprockets on both ends of said drum, the pitch diameter of the sprockets being substantially the same as the diameter of said 10 drum, a pair of sprocket chains engaging said sprockets, said sprocket chains being substantially the same length as said curtain and carrying said supporting rods, and means for intermittently moving said sprocket chains so as to 15 raise said sheets from said storage portion over said drum, the sheets moving from the drum to the storage space under the force of gravity.

3. A display sign having in combination, a plurality of sheets arranged as a continuous curtain, a continuous track for guiding said sheets, a storage portion in the lower region of said track, means for intermittently moving said curtain in said track, and a rigid plate against which 20 said sheets contact in the display position. 25

4. A display sign having in combination a plurality of sheets arranged as a continuous curtain, sprocket chains substantially the same length as said curtain, means for securing said curtain to said sprocket chains, means for guiding said sprocket chains, means for intermittently moving said sprocket chains so as to bring 30 said sheets to a display position, and a rigid substantially vertical plate against which said sheets contact in the display position. 35

BENTON N. REAMER.
